RADIO RECEIVING APPARATUS

Edwin A. Gustafson, Chicago, Ill., assignor to
 Johnson Laboratories, Inc., Chicago, Ill., a corporation of Illinois

Application March 5, 1934, Serial No. 714,019

3 Claims. (Cl. 171—242)

The invention relates to tuning systems for radio-receiving apparatus and particularly to the type which includes inductance tuning, wherein are included relatively adjustable plates, one of which carries an inductance coil, and the other of which carries a magnetic core, and the invention involves a new arrangement of the parts of such an apparatus whereby they may be readily dismantled, repaired and reassembled.

The invention will best be understood if reference be had to the accompanying drawing in which—

Figure 1 is a plan view, partly in section, showing the essential elements of the invention;

Figure 2 is a sectional view taken on the line 2—2 of Figure 1, the parts within the casing of the apparatus being shown in elevation, and

Figure 3 is a sectional view taken on the line 3—3 of Figure 1.

Referring to the drawing, 1 is a casing of usual character, in which the operative parts of the apparatus are assembled.

Within and secured to this casing is a plate 2 on which are mounted housings 3 for inductance coils 4 and their associated elements, all of which constitute no part of the invention and, therefore, require no description. These housings 3 are removably secured to the plate 2 by screws 5 which enter flanges of the plate.

The coils 4, their mountings 6, and their associated elements, are removably secured to the housings 3 by screws 7, each of which extends through a flange 8 of a housing and engages a hole in a mounting 6.

The separability of these parts of the device, and the absence of any proximate elements such as heretofore have been associated therewith, enable the user to readily gain access to the inductance coil 4 or any other element which requires attention.

The cores 9 and their housings 10 are carried by a plate 11, and all of these elements constitute an adjustable unit, the actuating means for the unit being a screw-threaded shaft 12 that extends inward through the casing 1, engages a screw-threaded opening 13 of the plate 11, and, at its inner end, enters a bearing 14 in the plate 2, the inner end being provided with a collar 15 and a shoulder 16, between which the plate 2 is

disposed, in order to prevent the shaft 12 from moving longitudinally.

The advantages of this invention are due to the fact that a housing and a coil and its associated elements may be assembled and conveniently tested while still accessible and before the housing is united with the other elements of the apparatus, and also that, since the housing which includes the coil is detachably mounted on that side of the fixed plate which is opposite the side that is proximate the adjusting device of the apparatus, the housing may readily be removed without detaching other elements of the apparatus whenever it becomes necessary to gain access to and examine or repair the inductance coil or its associated elements.

A further advantage of the invention, due to the simplicity of the apparatus, is that its manufacture is facilitated and its cost reduced.

Having thus described my invention, what I claim is:

1. A tuning system for radio-receiving apparatus, including a fixed plate, a removable housing disposed at one side of and carried by said plate, a removable inductance coil carried by said housing, a movable plate disposed at the other side of said fixed plate, a core carried by said movable plate and aligned with said inductance coil, and an adjusting mechanism for said movable plate and said core.

2. A tuning system for radio-receiving apparatus, including a fixed plate having an opening, a housing disposed at one side of and carried by said fixed plate, an inductance coil in said housing, a movable core aligned with said inductance coil and the opening of said fixed plate, and having an annular slot for the reception of said inductance coil, and an adjusting mechanism for moving said core until it substantially surrounds said inductance coil.

3. A tuning system for radio-receiving apparatus, including a fixed plate, a housing that is open at one end and is substantially closed at the other end, and also is removably attached at its open end to said plate, a removable inductance coil disposed within and supported by said housing, a magnetic core having an annular slot for the reception of said inductance coil and movable relatively to said inductance coil, and means for moving said core.

EDWIN A. GUSTAFSON.
